UNITED STATES PATENT OFFICE

FRED P. BARBOUR, OF DENVER, COLORADO

COMBINED DESK AND INVALID'S TABLE

Application filed January 12, 1931. Serial No. 508,109.

This invention relates to improvements in invalids' tables and desks of the type employed more particularly by people who are sick and lying in bed, but which can also be used by a person sitting up, and can be supported on a desk or a table, or on the person's lap.

It is the object of this invention to produce a compact and simple device that shall be provided with means for supporting it from any supporting surface, such as the surface of a bed or the top of a table or desk and which shall also be especially well adapted for being supported on a person's lap while he is sitting in a chair. This device is provided with a movable top or cover member that can be raised to any desired inclination with respect to the base and which shall be provided on one edge with a strip that will hold books or papers from sliding downwardly. Means is also provided for supporting the cover in any desired angle with respect to the top of the base.

The device is also provided with a drawer that can be used for stationery and for other articles so that these can be kept convenient for use whenever the desk is employed. In order to make the device suitable for being supported on a table or on a bed or on a person's lap, the end members of the base portion are each made of two parts hinged together and foldable inwardly underneath the drawer so that they can be folded when the device is supported on a desk or table and in this way the device will be lower than if the side members were not foldable.

Having thus described the object of the invention and briefly described its construction, the same will now be described in detail, and for this purpose, reference will be had to the accompanying drawings in which the preferred embodiment of the invention has been illustrated, and in which:

Fig. 1 is a perspective view showing the device in operative position;

Fig. 2 is an end view of the device adjusted in the manner shown in Fig. 1; and

Fig. 3 is a section taken on plane 3-3, Fig. 2.

In the drawings, reference numeral 1 rep-

resents the end members of the base and these have their upper edges connected by means of strips 2. These strips may be secured directly to the upper edges as shown in Fig. 2 or they may be notched into the end members in such a way that their upper surfaces will be flush with the upper edges of the end members. Each end member is made of two parts 3 and 4. Parts 4 are connected with parts 3 by means of hinges 5 that permit the lower portions of the end members to be turned inwardly into the position indicated by dotted lines in Fig. 3. The inner surfaces of parts 3 are provided with cleats 6 that engage in grooves in the side members 7 of the drawer. The drawer has a bottom 8 and an outer end member 9 and also a corresponding inner-end member which is not shown in the drawings. A cover or desk member 10 is hinged to the front edge of the strip 2 by means of hinges 11 as clearly shown in Fig. 2. The hinged edge of member 10 is provided with a strip 13 that serves to hold books or papers from sliding downwardly when the cover member is in inclined position. For the purpose of supporting member 10, I have provided a means comprising two arms 14 and 15 that is hingedly connected at 16 by means of a bolt having a butterfly nut 17. The upper end of arm 14 is connected with a bracket 18 secured to the under side of the cover member and the lower end of arm 15 is pivotally connected with part 3 by means of a pivot 19. There is one of these supporting members at each end and after the top has been adjusted to the desired inclination, the nuts 17 are tightened, thereby clamping members 14 and 15 against relative movement, whereby the cover member is held in adjusted position. When the device is not in use, the nuts 17 are loosened and the cover member is dropped down so that it rests on the upper surface of strips 2. When the device is to be used as an invalid desk or table by a person lying in bed, the end members are supported on the covers of the bed, one member being on each side of the person's body and the top 10 is adjusted to the inclination found most satisfactory for reading, if the desk is to serve as a support for a paper or a book. If the de-

vice is to be used for supporting a tray, the top 10 is laid down onto the strips 2 as above explained in which position it serves as a satisfactory support for a food tray. If the 5 person employing the device is seated on a chair, the device is placed on his lap with the sides 4 extending downwardly on the sides of the person's legs and by exerting a slight pressure against the inner surfaces of 10 the end members, the device is securely held in the lap and can be used for supporting a book or paper or as a writing desk for supporting paper and can also be employed as a drafting table in making drawings or 15 sketches.

The drawer has been shown as slidably connected with the ends, but it is also possible to build a drawer stationary in which case access to the interior of the drawer must 20 be obtained through the opening between strips 2.

From the above description it will be seen that I have produced a very simple and substantial device that is especially well adapted 25 for use by invalids that are lying in bed and which is also equally well adapted for use by persons sitting up, as it can be supported on the lap in the manner described or supported on another desk or a table. The means for 30 adjusting the inclination of the top makes it possible to so position the several parts that the best inclination for comfortable reading can be obtained when the device is used for supporting a book or a paper.

35 Having described the invention, what I claim as new is:

A combined invalid table and desk comprising, in combination, a base having two spaced, parallel end members, the upper ends 40 of the end members being connected to a top member, a drawer located between the end members directly beneath the top member, each end member being formed from two pieces connected by hinges, the lower portions 45 of the ends being foldable inwardly towards each other, a cover member having its front edge hingedly connected with the front edge of the top members and means for supporting the cover member in inclined 50 position with respect to the top member.

In testimony whereof I affix my signature.
FRED P. BARBOUR.
